(57) **CLAIM**

The ornamental design for a pressure tank for liquefied gas, as shown and described.

DESCRIPTION

FIG. 1 is a perspective view of a pressure tank for liquefied gas showing our new design;

FIG. 2 is a front view thereof; the back view being a mirror image of the front view;

FIG. 3 is a left side view thereof; the right side being a mirror image of the left side;

FIG. 4 is a top view thereof; the bottom view being a mirror image of the top view; and,

FIG. 5 is an enlarged view of a portion of the claimed region shown in FIG. 1.
